SPOUT UNIT

Paul R. Maguire, Los Angeles, Calif., assignor to Adams Rite Manufacturing Company, Glendale, Calif., a corporation of California

Filed Aug. 29, 1966, Ser. No. 3,632

Term of patent 14 years

(Cl. D91—3)

FIG. 1 is a perspective view of a spout unit showing my new design;

FIG. 2 is a top view of the same;

FIG. 3 is a front elevational view thereof;

FIG. 4 is a rear elevational view thereof; and

FIG. 5 is an elevational view taken from one side thereof.

The fragmentary broken line representation of a faucet assembly in the five figures is for purposes of illustration only.

I claim:

The ornamental design for a spout unit, substantially as shown and described.
